UNITED STATES PATENT OFFICE

ROBERT G. LE TOURNEAU, OF STOCKTON, CALIFORNIA

SCRAPER

Application filed January 5, 1931. Serial No. 506,521.

This invention relates to scrapers of the wheel supported and large capacity type, and particularly to such scrapers in which the discharge of the load is effected by moving the back plate or endgate of the bowl of the scraper forwardly, so that the load is positioned over the front end of the bowl. Structures having this feature are shown for instance in my Patents Nos. 1,530,779 dated 5 March 24, 1925, and 1,598,864 dated 10 September 7, 1926.

The principal objects of my present invention are to provide what I believe to be a novel mechanism for controlling the movement of the endgate, and also a novel mechanism for controlling the raising and lowering of the rear supporting wheels of the scraper, which determines the level of the bowl and consequently governs the position 20 of the same for loading or dirt conveying purposes.

These objects I accomplish by means of such structure and relative arrangement of parts as will fully appear by a perusal of 25 the following specification and claims.

In the drawings similar characters of reference indicate corresponding parts in the several views:

Fig. 1 is side elevation of my improved 30 scraper shown in its loaded position.

Fig. 2 is a similar view showing the bowl in its carrying position.

Fig. 3 is a top plan view of the scraper.

Fig. 4 is a fragmentary enlarged longitudinal section of the scraper showing the 35 endgate partly advanced.

Fig. 5 is a fragmentary section of the main frame beam of the scraper showing the front-end mounting of the endgate controlling 40 spring.

Referring now more particularly to the characters of reference on the drawings, the numeral 1 denotes the longitudinally extending main frame beam of the scraper—a 45 straight rigid member of hollow box section. A post 2 of similar nature depends from the forward end of the beam and is supported by a swivelly mounted truck 3 from which a tongue 4 extends forwardly for connection 50 to a tractor.

Disposed under the beam toward its rear end is the bowl of the scraper. This bowl comprises side plates 5 and a bottom plate 6 which terminates in a cutting blade 7 disposed some distance rearwardly of the forward ends of the side plates. A hollow cross beam 8 is secured to the under side of the main beam and extends between and is secured to the side plates adjacent their forward ends. A tension bar 9 extends between the beam 8 and the blade centrally of the ends of the latter to hold the same against downward deflection. The bowl and beam 1 are additionally connected together so as to be maintained in rigid unitary association by diagonal forwardly angled beams 10 extending between the side plates and the beam 1 ahead of the cross beam. The back end of the bottom plate is reinforced by a cross-beam 11 under the same, from the ends of which short arms 12 project upwardly and rearwardly. On their upper ends these arms have pivotal connection with rearwardly and upwardly projecting members 13 which are connected to a common cross-beam 14 disposed rearwardly of the bowl. Arms 15 depend rearwardly and downwardly from the beam 14 intermediate its ends and form supports for the spindles or axles of the rear wheels 16 of the scraper.

A rigid lever 17 projects upwardly from the beam 14 to one side of the beam 1 and has a forwardly extending bar 18 pivoted on its upper end. This bar is disposed above the plane of the beam 1 and projects forwardly to one side of the same to a termination ahead of the bowl. A multiple sheave block 19 is rigidly secured to the under side of the bar at its forward end, this block being associated with a roller 20 which rides on a rail 21. This rail is fixed in parallel connection with the beam 1 to one side of the same and ahead of the beam 8, the engagement of the roller with the rail being maintained by the weight of the bar.

A cable 22 is anchored at one end on the casing of a multiple sheave block 23 which is rigidly secured on the beam 8 in longitudinal alignment with the block 19. The cable extends thence back and forth between the

80

85

90

95

100

blocks 23 and 19 over the various sheaves and thence forwardly and over a single sheave 24. This latter sheave is swivelly mounted on the outer end of a cross arm 25 which is fixed in connection with and above the beam 1 at its forward end. From the sheave 24 the cable extends to a winding drum on the tractor, this drum being preferably mounted in connection with a power unit of the type shown in my copending application for patent, Serial No., 512,979, filed February 2, 1931.

By reason of this arrangement it will be seen that a pull on the cable draws the sheave block 19 and consequently the bar 18 rearwardly. This exerts a rearward push on the lever 17, causing the wheel supporting arms 15 to be depressed and thus lowering the wheels relative to the bowl against the resistance offered by the weight of the latter and its load. With this position of the wheels the bowl will obviously be raised clear of the ground a certain distance depending on the extent to which the bar 18 has been forced rearwardly. The block 23 is disposed on a level below that of the block 19, so that a pull on the cable exerts a downward pressure on the bar and aids in holding the roller engaged with its rail. Upon the winding drum to which the control cable 22 is attached being released, the weight of the parts causes the wheels to be relatively raised and the bowl lowered as will be evident, thus avoiding any undue slack of the cable being had with such release of the drum.

The back of the bowl is in the form of a vertical plate 26 unattached to the side plates, and braced by upright beams 27 and a cross-beam 28 near the bottom and to which said uprights are connected.

The uprights extend past the beam 1 adjacent the opposite sides of the same and are rigidly connected to a supporting carriage 30 disposed above said beam. This carriage has rollers 31 engaging the top surface of the beam and to the rollers 32 engaging the sides of the beam, so that said carriage may travel with a minimum of friction and with no tendency to stick. An additional roller 33 extends between and is supported by the uprights 27 and engages the under face of the beam 1. The uprights are connected to the carriage adjacent its rear end and diagonal beams 34 extend between the carriage toward its forward end and the uprights 27 intermediate their ends. A multiple sheave block 35 is rigidly mounted on the carriage at its front end, while a similar block 36 is mounted on the main beam 1 some distance in front. A cable 37 is anchored at one end on the casing of the block 35 and extends thence back and forth between said block and the block 36 and over the various sheaves. The cable then extends forwardly to and over a single sheave 38 which is swivelly hung from the opposite

end of the cross-arm 25 to that on which the sheave 24 is mounted. From this sheave the cable extends to another winding drum of the tractor-mounted power unit previously mentioned. It will therefore be seen that with a pull on said cable the carriage and the endgate will be drawn forwardly, thereby effecting the discharge of the load from the forward end of the bowl. The endgate does not of course tend to return of itself to its normal position at the back of the bowl, and to automatically return the endgate to such position when the winding drum is released, and without any undue slack of the control cable being had I provide the following means: Mounted in the main beam 1 is a longitudinally extending compression spring 39. The rear end of the spring abuts against the rear end closure of the main beam, while its forward end bears against a head 40 slidably in the beam. A cable 41 is attached to this head and extends thence inside the coils of the spring to the rear end of the beam and thence over a sheave 42 fixed in connection with said beam at its rear end beyond the spring. Passing about and under the sheave the cable is attached to the endgate adjacent its upper end or just below the roller 33, as shown in Fig. 4. It will thus be seen that when the endgate is drawn forwardly the spring is placed under compression. When the pull on the cable 37 is released the expanding spring draws the endgate, through the medium of the cable 41, back to its normal position at the rear ends of the side plates. This spring is sufficiently strong so as to impart such movement to the endgate against the inevitable drag of the cable and that caused by the weight of the gate itself.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A scraper comprising a bowl having side plates and a bottom plate, an endgate for the bowl, disposed between the side plates, means mounting said endgate for movement lengthwise of the bowl and parallel to the bottom plate, a longitudinal beam rigid with and above the bowl, a carriage supported on the beam for movement along the same, rigid connections between the carriage and endgate whereby the latter forms a rigid unit with the carriage, means applied to the carriage to pull the same forwardly, a spring mounted on the beam ahead

of the engate, and means between the endgate and spring to compress the latter when the endgate is pulled forwardly, whereby when the pulling pressure is released, the spring will act to retract the engate.

5 2. A scraper comprising a bowl having side plates and a bottom plate, an endgate for the bowl, disposed between the side plates, means mounting said endgate for movement lengthwise of the bowl and parallel to the bottom plate, a longitudinal beam rigid with and above the bowl, a carriage rigid with the endgate and slidably supported on the beam, a sheave block secured on the 10 forward end of the carriage, another sheave block secured on the beam ahead of the carriage, and a cable anchored on one block and extending thence back and forth over the sheaves of the blocks and then forwardly of 15 and beyond the beam for connection to a winding drum.

3. In a scraper, a bowl, a transverse beam behind the same, means pivotally supporting the beam from the bowl, arms rigid with 25 and projecting rearwardly from the beam, wheels supported on the rear ends of the arms, a lever rigid with and upstanding from the beam, a bar connected to the upper end of the lever and extending thence forwardly, and means applied to the bar for 30 pushing the same rearwardly.

4. In a scraper, a bowl, a transverse beam behind the same, means pivotally supporting the beam from the bowl, arms rigid with 35 and projecting rearwardly from the beam, wheels supported on the rear ends of the arms, a lever rigid with and upstanding from the beam, a bar connected to the upper end of the lever and extending thence forwardly, 40 a horizontal rail extending lengthwise of and under the bar, a member on the forward end of the bar engaging the rail, and means applied to the bar to push the same rearwardly and to also exert a downward pressure on the 45 forward end of the bar.

5. A scraper comprising a bowl and endgate for the bowl, means mounting said endgate for movement endwise of the bowl, a hollow longitudinal beam rigid with and above the bowl, a carriage supported on the beam for movement along the same, rigid connections between the carriage and endgate whereby the latter forms a rigid unit with the carriage, means applied to the carriage to pull the same forwardly, a compression 50 spring enclosed in the beam ahead of the endgate; the rear end of the spring being held against movement, a head movable along the beam and engaged by the forward end of the spring, a sheave mounted on the beam rearwardly of the endgate and spring and a flexible member connected at one end to the endgate and extending thence to and about the sheave and along the spring to a 55 connection with the head.

6. A scraper comprising a bowl and endgate for the bowl, means mounting said endgate for movement lengthwise of the bowl, a longitudinal beam rigid with and above the bowl, a carriage riding on top of the beam for movement along the same, rigid connections between the carriage and endgate to the sides of the beam whereby said endgate is rigid with the carriage, and means above the beam and directly applied to the carriage to pull the same along the beam.

In testimony whereof I affix my signature.
ROBERT G. LE TOURNEAU.
